UNITED STATES PATENT OFFICE.

SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

SUSTAINING DEVICE FOR VAPOR-CONVERTERS.

1,227,766.

Specification of Letters Patent.

Patented May 29, 1917.

Application filed July 14, 1915. Serial No. 39,796.

To all whom it may concern:

Be it known that I, SIDNEY W. FARNSWORTH, a citizen of the United States, and a resident of Pittsburgh, in the county of Allegheny and State of Pennsylvania, have invented a new and useful Improvement in Sustaining Devices for Vapor-Converters, of which the following is a specification.

My invention relates to arc-sustaining devices for vapor converters, and it has for its object to provide a device of the character specified that shall be simple and rugged in construction, effective in operation, and extremely efficient in its consumption of energy.

The single figure of the accompanying drawing is a view, partially in section and partially in elevation, of a vapor converter embodying a preferred form of my invention.

In the operation of vapor converters of the type wherein alternating current is converted into unidirectional current, it is necessary to provide a sustaining or keep-alive anode to energize the cathode at times when the supply circuit is inactive. This sustaining device has hitherto commonly taken the form of a refractory conducting rod extending into the converter to a point adjacent the surface of the cathode and connected to a suitable source of exciting current, either direct or alternating, with such phase relation to the supply that a keep-alive arc is maintained at all times when the main converting arc would tend to go out. Suitable means are provided for initiating an arc between the keep-alive electrode and the cathode, either by causing the two to make and break contact or by impressing a high voltage therebetween. In a vapor converter of large capacity, the cathode is necessarily provided with an extended active cathode surface and the cathode end of a keep-alive arc tends to wander in an erratic manner over this surface. As the upper end of the keep-alive arc is necessarily more or less fixed in position upon the lower portion of the keep-alive anode, the keep-alive arc varies greatly in length and in voltage consumption. When the keep-alive arc has a

minimum length, the potential consumed thereby need not exceed 10 or 15 volts whereas, if the arc is drawn out to a considerable length, it may easily consume as much as 30 volts. It has therefore been necessary hitherto to provide a keep-alive source providing from 35 to 40 volts, together with a suitable rheostat for reducing or masking the effects of changes in the arc resistance upon the arc current.

By my invention, I mount a suitable perforated plate of conducting material a short distance above the cathode surface and extending over the entire active portion thereof. The perforations in said plate are of such size that the main converting arc may flow therethrough without difficulty. A keep-alive electrode of the usual form projects through one of the perforations in said plate so that the arc may be initiated in the said manner and said keep-alive electrode is furthermore connected, either within or without the container, to said perforated plate. By this structure, the keep-alive arc, when initiated, readily transfers itself to the plate and the tendency to wandering at the cathode end of the keep-alive arc tends to move the entire arc about on the surface of the cathode, a minimum length being substantially maintained at all times. It is therefore necessary to provide a source of keep-alive circuits having only sufficient voltage to supply the minimum amount consumed by the keep-alive arc, unnecessary resistance and resultant waste is eliminated, little or no attention is necessary, and the keep-alive plate outlives the converter because of its large cross section and heat-radiating capacity.

Referring to the accompanying drawing for a more detailed understanding of my invention, I show a vapor converter of the usual type provided with a container 1, a main anode 2 and a cathode 3, the latter composed preferably of mercury. A keep-alive anode 4 of the usual type projects through the cover of the container 1 and is insulated therefrom by suitable means 5. The keep-alive anode 4 terminates a short distance above the cathode 3, prefer-

ably in a tip 6 composed of a refractory material, such, for example, as tungsten. The keep-alive anode 4 is shielded from the main power arc by a suitable shell 7 and is energized from a source 8 through an adjustable rheostat 9. An arc-controlling ring 10 composed of refractory insulating material, such, for example, as quartz or porcelain, is placed in the central portion 10 of the cathode 3 and supports a plate or grid 11 on its upper edge, said plate or grid being preferably composed of refractory conducting material, such, for example, as cast iron or stamped steel. The 15 keep-alive anode 4 projects through one of the perforations in the plate 11 and is connected thereto by a flexible connecting device 12.

Having thus described the structure of a 20 converter embodying my invention, the operation is as follows: At the outset, the keep-alive arc is struck between the tip 6 and the cathode 3, either by successively lowering and raising the keep-alive anode 25 4 by a suitable operating device (not shown) or by slopping or splashing the cathode material. The lower end of the keep-alive arc will not remain immediately below the point 6, but, for reasons which are not yet fully 30 understood, it will tend to wander about on the surface of the cathode 3 and at a given instant may assume, for example, a position 13. Under these conditions, rather than extend itself over the path 14, the upper end of 35 the keep-alive arc will transfer itself to the grid 11 and will move to a point 15 so that an arc path 16 of substantially minimum length will be provided. Any subsequent movement of the point 13 will be followed 40 by a like movement of the point 15 and thus the entire keep-alive arc will move about on the surface of the cathode.

I may, if desired, withdraw the anode 4 through the grid 11 in starting, thus causing 45 the keep-alive arc to operate solely from said grid. Furthermore, I may so modify the grid 11 that it serves the additional function of a cathode shield, preventing the direct emission of mercury globules against 50 the anode, but modifications of this character form no part of the present invention and are covered in separate applications.

An extremely valuable feature of my invention exhibits itself in converters designed 55 for railway use wherein the cathode 3 is subject to continual splashing and vibration and where it is therefore essential that the keep-alive electrode be disposed at much greater distance from the cathode than 60 would otherwise be necessary. Were the tip 6 to be raised to the necessary height, an excessively long path for the keep-alive arc would be produced if the spot 18 wandered away from its preferred position. By

disposing a grid 11 at the desired height 65 above the cathode 3, an arc length may be chosen which has minimum values for safety from extinguishment from splashing but which, at the same time, does not demand an excessively high operating voltage. 70

While I have shown my invention in its preferred form, it will be obvious to those skilled in the art that it is susceptible of various minor changes and modifications without departing from the spirit thereof, 75 and I desire, therefore, that no limitations shall be placed thereupon except such as are imposed by the prior art or are specifically set forth in the appended claims.

I claim as my invention:

1. In a vapor electric device, the combination with a cathode, of a keep-alive anode substantially coextensive with the active surface thereof, said keep-alive anode being provided with openings for the passage of 85 the converting arc to any part of the cathode surface.

2. In a vapor electric device, the combination with a cathode, of a keep-alive anode extending over substantially the entire active surface thereof, but so perforated as to exert substantially no shielding action 90 thereupon.

3. In a vapor electric device, the combination with a cathode, of a keep-alive anode 95 extending over substantially the entire active surface thereof and equally spaced therefrom throughout its area, said anode being provided with a plurality of perforations therethrough to minimize the shielding action thereof.

4. In a vapor electric device, the combination with a cathode having an extended active surface, of a reticulated keep-alive anode provided with portions extending in 10 proximity to all portions of said cathode surface.

5. In a vapor electric device, the combination with a liquid cathode having an extended active surface, of a reticulated conducting plate adjacent, substantially parallel to and coextensive with, said cathode surface, and connections from said plate to a keep-alive circuit, whereby said plate is adapted to operate as a keep-alive anode. 11

6. In a vapor electric device, the combination with a liquid cathode having an extended active surface, of a reticulated conducting plate adjacent, substantially parallel to and coextensive with, said cathode surface, a keep-alive anode extending through said plate and into proximity to said cathode, and a connection from said keep-alive anode to said plate, whereby a keep-alive arc initiated by said anode may be 12 transferred to, and operated from, any portion of said plate.

7. The combination with a vapor electric

device provided with main electrodes and a reticulated keep-alive anode, of means for causing the main converting arc to operate through the perforations in said anode.

5. 8. The combination with a vapor electric device provided with an extended cathode, of means for permitting the keep-alive arc

to follow the main cathode spot while maintaining a substantially uniform predetermined length.

In testimony whereof, I have hereunto subscribed my name this 28th day of June 1915.

10

SIDNEY W. FARNSWORTH.
